MEANS FOR MASSAGING, VIBRATING, EXERCISING, RELAXING AND HEAT TREATING PARTS OF THE HUMAN BODY

Frank J. Sibert, East Orange, N.J.

Application December 19, 1956, Serial No. 629,297

3 Claims. (Cl. 128—24.1)

This invention relates to ways and means for massaging, vibrating, exercising, relaxing and heat-treating parts of the human body collectively or in predetermined sequences. The means and method of operation to be hereinafter described are especially adapted for use in hospitals, rehabilitation and office practice, rest rooms and beauty salons.

From the description which follows, it will be readily understood that the principal object of my invention is to substantially obviate all of the disadvantages of the present art and to allow massaging, vibrating exercising, relaxing and heat-treating parts of the human body to be done efficiently.

This device can be adapted to the individual requirements of the user instead of the user to the device.

It is also to be understood that although I may use, in my means, a special coin device of my own invention, it is not essential to the operation of the means.

In attaining the principal object, other ancillary objects will be observed from the following specification taken in connection with the annexed drawings wherein:

Figure 1 illustrates a semi-diagrammatical longitudinal section through the means employed in my method;

Figure 2 is a view similar to Figure 1 but showing a modified form of the means shown in Figure 1 to create leg, thigh, and ankle massage;

Figure 3 is a view similar to Figure 2 but of a still further modification showing the application of massaging, exercising and heat-treating to the buttocks, thighs, legs and ankles;

Figure 4 is a fragmentary sectional view through a modified form of body rest; and

Figure 5 is a fragmentary perspective section through one of the heat-treating massaging rollers.

In the drawings like numbers refer to corresponding parts.

A denotes the means as a whole which is composed of a supporting base structure B, a sliding body supporting unit B', a leg rest unit C, a fixed roller unit D, and a hinged roller unit E. The structure B is in the form of an elongated rectangular box having the side walls 1 and 2 and the ends 3 and 4. The top of the box is left open as indicated at 5. If desired, in order to strengthen the structure B, wall 6 and 7 may be placed as indicated in the drawings between the walls 1 and 2. However, these are not required as the structure is sturdy enough if they are omitted. The structure B, however, may be provided with an internal box-like unit 8 intended to be used as a storage bin for the units C, D and E when not in actual use. It is to be understood that the units C, D and E are required for various operations constituting functions and steps incorporated in my method and means. The units C, D and E are used singly or in co-acting relation, depending upon conditions and treatment from time to time. For instance, unit C may be used alone or combined with unit D or the unit E used alone. However, it will be noted from the drawings, that in all cases, the means always incor-

2

porates the use of the structure B and the body supporting unit B'.

It will be seen from the drawings that the unit B' does not occupy the entire upper area lengthwise of the structure B, and that it is slightly less in width than the inner width between the side walls 1 and 2 of the structure and thus does not contact either the walls 1 and 2 or the ends 3 and 4 of the structure B, so that it may be freely moved within these walls. Referring now again to the details of the structure B, this structure B is provided with a hand grip stretch rod, or bar 9 firmly attached to the end wall 3 of the structure B. The structure B may also be provided with a base or bottom 10. Attention is now directed to the construction of the body supporting unit B'. This unit B' is preferably of a flat, elongated, rectangular shape bed plate upon which infrared heating pads 13 may be placed over which is placed a suitable soft protective covering, and is attached as indicated at 11. Although I have shown several such pads in my drawing, it is to be understood that I may use only one or two such pads or dispense with them altogether, and use foam rubber padding as indicated at 12, or a combination of both. The bed plate of the unit B' may be recessed as shown at 14, and have attached thereto, two or more vibratory units 15. These units 15 are placed relatively near the opposite ends of the unit B' so that upon actuating these units, the position of the source of vibration imparted to the unit B' will be, as they are used selectively, either near the upper portion of the body of the person reclining on the unit B', or near the buttocks area, or under both areas, and not directly beneath the central spine. Attached also to the bed plate of the unit B' is a depending attaching piece 16, the purpose of which will be later described. Positioned in spaced relation longitudinally within the structure B and firmly attached to the side walls 1 and 2 thereof, are pocket members 17 in and upon which roller bearings 16 are adapted to ride and upon which the unit B' is allowed to be supported and roll. It will be seen from the drawings, that these rollers are not attached to the members 17 or the unit B' but are free to roll within the limits of the recesses in the members 17. In order to impart longitudinal movement to the unit B', I provide the motor 18, provided with suitable speed reduction which imparts movement to the cam 20 and ring mounting 19 by means of the shaft 21. The cam ring 19 has an integral link 22 which is pivotally attached to the depending member 16 attached to the unit B'. It will be understood from this description that by the action of cam member 20, the unit B' will ride longitudinally forward and backwardly within the confines of the structure B, the amount of travel being determined by the throw of the cam 20 and the speed by the reduction means.

Referring now to unit C. This unit is constructed similar to that incorporated in unit B' insofar that it may contain padding or heating pads and a vibrator 23, but it does not travel longitudinally, but, simply rests upon the side walls 1 and 2 and the end wall 4 of the structure B. The unit C is employed primarily in vibrating and heat-treating the legs while the body proper is being treated by stretching, vibrating, and massaging by the unit B'. Referring again to the structure B. The structure B is further provided near its end wall 4 with a motor 24 having co-acting therewith a disc-like member 25 provided with a pivoted connecting rod 26 which, when the unit C is being used, is allowed to remain idle, the purpose of the motor 24, the member 25 and the rod 26 being explained later.

The unit D is of radically different construction to that of unit C. This unit D is of triangular shape inside elevation and consists of two side frame members 27 be-

tween which are rotatably mounted rollers 28, arranged in an ascending and a descending series, which may be just rollers, cushioned rollers, or infra-red heating roller units. The unit D may be placed directly upon the top of unit C, the bottom of the side pieces 27 resting firmly upon the non-skid surface of unit C. In using unit D the buttocks are placed close to the forward end of the unit D and the upper leg over the first set of rollers 28, the calf and ankles contacting the second set of rollers 28. Thus, it will be seen that upon the movement of unit B' forward and backward, the unit D thru its rollers, will massage the legs and ankles, while leaving the under knee free from any injury by contacting unit D. In this arrangement, as well as that when unit C is used, the motor 24, disc 25 and rod 26 are not employed.

Unit E, although somewhat like unit D, is composed quite differently in detail. This unit is a composite hinged structure 29 composed of two hinged sections 30 and 31 hinged by a double hinged member 32, each of the sections 30 and 31 being provided with rollers, cushioned rollers, or infra-red roller heating units similar to 28 in unit D, the unit 31 being provided with a hinging base 33 so that the unit E may be hingedly attached to the structure B.

When the unit E is attached to structure B, the rod 26 is then attached to the compound hinge 32 and the section 30 of the unit E allowed to overhang the upper end of end wall 4 of the structure B.

It will be understood from this description, as well as by the drawings, that upon activating the motor 24, the unit E will be given a knee action motion extending rearward from the hinge 33 attached to the structure B. Thus, when unit E is employed, an exercising, and flexing of the limbs is achieved, as well as a massage of the thighs, legs and ankles, and to the buttocks, since the buttocks is placed directly in contact with the end of member 31 of the unit E. It will be also understood that before the unit E is mounted in the structure B, the members or units C and D are not in place upon the structure; the means also contemplates the use of a suitable timer, indicated at 34, a selective switch arrangement unit 35, and a coin unit 36. The means above described makes it possible to actuate any motor units independently, in unison, or groups, to select any part of its entire function alone or in combination with any other separate function and provides in one means the power to select any combination of massaging, vibrating, exercising, relaxing and heat-treating or stretching in any sequence desired, and for any duration without the need of a secondary means other than the use of parts of which it itself is composed.

Although I have shown only a few modifications and views of my means, it is to be understood I may make various minor modifications of my means without departing from the spirit of my invention, and all of the claims should be read in the light thereof.

I claim:

1. Means for massaging, vibrating, exercising, relaxing and heat-treating parts of the human body comprising a stationary supporting structure, a longitudinal, oscillat-

ing, reciprocating, vibrating body supporting area adapted to slide back and forth within the upper area of the stationary structure, anti-friction rollers co-acting with the body supporting area, at least two vibratory units mounted upon the body supporting area, heating elements mounted within said body supporting area, a motor adapted to impart back and forth motion to said body supporting area, a removable, cushioned massaging roller-grid hinged at its forward end to the foot of the stationary supporting structure, a heating element for the roller-grid and means for imparting massaging action to said roller-grid.

2. Means for massaging, vibrating, exercising, relaxing and heat-treating parts of the human body comprising a stationary supporting structure, a longitudinal, oscillating, reciprocating, vibrating body supporting area adapted to slide back and forth within the upper area of the stationary structure, anti-friction rollers co-acting with the body supporting area, at least two vibratory units mounted upon the body supporting area, heating elements mounted within said body supporting area, a motor adapted to impart back and forth motion to said body supporting area, a removable, cushioned massaging and flexing roller-grid, hinged at its forward end to the stationary supporting structure, and means contained within the stationary supporting structure for flexing said removable cushioned massaging and flexing roller-grid.

3. In a machine of the character described, a component functioning as a leg rest and comprising a series of ascending, and a series of descending, rollers, hingedly connected and over which a patient's legs may be moved transversely for massaging action, the ascending series of rollers being pivotally mounted at one end, and directly hinged at its other end to one end of the descending series, a first stationary support on which the other end of the descending series is free to slide, a second stationary support to which said ascending series is pivoted, said series being continuously movable to change the angle between them, motor-operated means for alternately increasing and diminishing the angle between the ascending and descending series of rollers by a raising and lowering action, whereby a knee action is produced for the purpose of simultaneously massaging a patient's legs while flexing and unflexing them, said means restricted to raise and lower both said series of rollers between a horizontal and an above-horizontal position.
